MODEL RACING CAR

Gordon Leonard Coppuck, Camberley, England, assignor to Bruce McLaren Motor Racing Limited, Colnbrook, Buckinghamshire, England

Filed Dec. 6, 1971, Ser. No. 205,459

Term of patent 7 years

Int. Cl. D21—01

U.S. Cl. D34—15 AJ

FIG. 1

FIG. 2

FIG. 1 is a top plan view of a model racing car showing my new design;

FIG. 2 is a front elevational view thereof;

FIG. 3 is a left side elevational view thereof, the right side being identical thereto;

FIG. 4 is a rear elevational view thereof.

I claim:

The ornamental design for a model racing car, as shown and described.
